UNITED STATES PATENT OFFICE.

PAUL SIMON, OF PERTH AMBOY, NEW JERSEY.

LIFE-SAVING SUIT.

1,141,273.

Specification of Letters Patent.

Patented June 1, 1915.

Application filed January 9, 1915. Serial No. 1,332.

To all whom it may concern:

Be it known that I, PAUL SIMON, a subject of the King of Hungary, residing at Perth Amboy, in the county of Middlesex and State of New Jersey, have invented new and useful Improvements in Life-Saving Suits, of which the following is a specification.

This invention relates to a life saving suit for aeronauts and has as its principal object to provide a device of this character which persons engaged in the above said pursuit may continuously wear during flights in the air without too much inconvenience and which is always ready for use in emergency cases.

A further object of my device is to save the life of a person in case of a fall from an air-craft either on land or on water.

20 A still further object of my invention is to provide a device which will afford the utmost possible convenience to the wearer thereof while floating in water.

My present invention is practically the same as another invention for Letters Patent on which I am applying at the same time, relating to a life-saving suit for passengers aboard water-craft, with such changes only as are necessary to attain the further objects the present invention has and reference will be had in the description of my present invention to the before-mentioned application to avoid repetition.

In the accompanying drawing: Figure 1 is a side elevation and Fig. 2 a rear elevation of my device worn by a person, ready for use. Fig. 3 is a plan view and Fig. 4 is a side elevation of a part of my device.

The same reference character designates the same part throughout the several views.

Referring more particularly to the drawing, 5 is a suit substantially the same as described in the application referred to on the foregoing page, having air-tight pockets 6 and 7 at the front and back portions, respectively, and channels 8 made of the same material connecting them at either side with air-tight pockets 9 and 10 on the leg-portions. The difference is that the pocket 7 at the back portion

of the suit 5 is continued in a hose 11 of the same material, connecting it with a helmet-like bag 12 secured to the head of the wearer, also of airtight material, fitting closely on the head and which also will be 55 inflated by the air blown into the pockets through the pipe 13 and air-valve 14. The sleeves 15 are the same as in the suit described in my application above referred to.

The shoe-portion 16 of the suit is, in my present invention, provided with rubber soles 17 having ears such as 18 a pair near the toe portions of each, and one pair near the heel portions of each, and attached by straps such as 19 to each rubber sole is another rubber sole 20, the straps passing through the ears 18 with which the rubber soles 20 are also provided. Each of the rubber soles is provided at the sides facing each other with studs as 21, two side-by-side near 70 the toe portion and one each near the heel portions. Springs such as 22 are between each pair of soles held in position by the studs 21 engaging the ends thereof.

A person wearing this suit, if falling 75 from the air, will always fall feet downward, the center of gravity being well below the waist on account of the air-filled pockets on the front and rear-portions of the suit and the helmet-like bag on the head 80 and also on account of the additional weight of the double soles attached to the feet. The springs between the rubber soles will considerably mitigate the force of the impact on landing on the ground and prevent 85 a fatal accident. On the other hand, falling into water, the person will be saved from drowning by the air-tight pockets keeping the wearer of the suit afloat and the suit being of watertight material, eliminates much of the inconvenience of the direct contact of the water with the body of 90 the person.

Having thus described my invention, what I claim is:

A life-saving suit for aeronauts comprising, in combination, a suit made of watertight material, provided with a plurality of airtight pockets and an air-tight helmet all communicating with each other through 100

channels made of the same material, means for inflating said air-tight pockets and helmet with air from the lungs of the wearer, said suit terminating at the lower extremities in double rubber soles connected with each other by straps, springs between each pair of soles and means integral with said

soles to keep said springs securely in position, substantially as and for the purpose set forth.

PAUL SIMON.
